Primary Examiner—Robin V Webster*(74) Attorney, Agent, or Firm*—Banner & Witcoff, Ltd.(57) **CLAIM**

The ornamental design for a bucket, as shown and described.

DESCRIPTION

FIG. 1 is a top front right perspective view of a bucket showing our new design;

FIG. 2 is a bottom view thereof;

FIG. 3 is a top view thereof;

FIG. 4 is a left side view thereof;

FIG. 5 is a right side view thereof;

FIG. 6 is a front view thereof;

FIG. 7 is a rear view thereof; and,

FIG. 8 is the bottom rear right perspective view thereof.

The dash-dot-dash lines immediately adjacent to the shaded areas represent unclaimed boundaries of the claimed design. The dot-dot lines showing the remainder of the bucket are for illustrative purposes only and form no part of the claimed design.
